[57] CLAIM

The ornamental design for a carrier for bottles or the like, as shown.

DESCRIPTION

FIG. 1 is a top perspective view of a carrier for bottles or the like showing my new design;

FIG. 2 is a side elevational view thereof;

FIG. 3 is an end elevational view thereof;

FIG. 4 is a top plan view thereof; and

FIG. 5 is a bottom plan view thereof on a reduced scale.
